DESIGN FOR A CLAMPING DEVICE

Adolph T. Stein, Chicago, Ill., assignor to J. W. Speaker Corporation, Chicago, Ill., a corporation of Illinois

Application May 26, 1938, Serial No. 77,414

Term of patent 14 years

To all whom it may concern:

Be it known that I, Adolph T. Stein, a citizen of the United States, residing at Chicago, in the county of Cook and State of Illinois, have invented a new, original and ornamental Design for Clamping Device, of which the following is a specification, reference being had to the accompanying drawing, forming a part thereof.

In the drawing:

Figure 1 is a plan view of the clamping device showing my new design;

Figure 2 is a side elevational view of the same; and

Figure 3 is an end elevational view of the same.

I claim:

The ornamental design for a clamping device, as shown.

ADOLPH T. STEIN.
